THOMAS J. CRAVEN AND DANIEL J. CRILLY, OF DETROIT, MICHIGAN.

CABLE-GRIP.

1,272,392.

Specification of Letters Patent. Patented July 16, 1918.

Application filed March 31, 1917. Serial No. 158,813.

To all whom it may concern:

Be it known that we, THOMAS J. CRAVEN, a citizen of the United States, and DANIEL J. CRILLY, a subject of the Kingdom of Great Britain, both residing at Detroit, in the county of Wayne and State of Michigan, have invented a new and useful Cable-Grip, of which the following is a specification.

This invention relates to cable grips, and 10 has for its object the provision of a simple and efficient coupling for connecting the terminals of ropes or cables together or to other objects to be made fast or engaged thereby, in which provision is made for securing the 15 end of the cable in looped formation about the object to be connected and confining the loop under the wedging pressure of a gripping jaw actuated by the tensile stress exerted upon the cable, and wherein the arrangement 20 is such as to adapt the grip or coupling to a large range of uses, enabling it to be readily adjusted for attachment or when in use and to be quickly released for disengagement.

A preferred structural embodiment of the 25 essential features of the present invention is described in the following specification and illustrated in the accompanying drawings, in which:

Figure 1 is a view in side elevation of the 30 grip coupling embodying our invention and showing the cable connected thereby as when in operation.

Fig. 2 is a central vertical section through the coupling in the connected position of 35 Fig. 1.

Fig. 3 is a transverse vertical section on dotted line 3—3 of Fig. 2.

Fig. 4 is a horizontal section on dotted line 4—4 of Fig. 2.

Referring to the parts of the device by the corresponding characters of reference throughout the views of the drawings, 1 represents the body of the coupling which consists of a hollow sheet metal casing 45 formed with spaced parallel side walls joined together at opposite edges by opposed outwardly curved walls 2 and 3, and having openings 4 and 5 respectively in opposite ends thereof. The inner arcs of the 50 walls 2 and 3 of the casing are formed to provide semi-circular bearing surfaces 6 and 7 respectively to coincide with and receive the respective leads 8 and 9 of the looped end of a cable 10 extended through the openings 4 and 5 of said casing, the wall 2 of the casing being extended inwardly and upwardly of

the opening 4, as at 11 to engage and position the entering cable in substantially central vertical alignment with the body of the casing, and with the looped portion of the 60 cable extending through the opening 5 thereof.

Pivotedly mounted centrally upon a stud 12 anchored to extend transversely and substantially centrally through the parallel 65 side walls of the casing is a cam shaped clutch or gripping jaw 13. This jaw, which is adapted to swing or rock upon the stud 12 receives said stud through an elongated aperture 14 which permits of a limited transverse movement of the jaw thereon, and the ends of the jaw are formed with reversely opposed eccentric or cam faces 15 and 16 which are peripherally concaved to conform with and engage respectively the inner arcs 75 of the leads of the looped cable, as shown in Figs. 2 and 4.

It will be noted that the minor distance between the opposed cam faces of the jaw is such as to provide clearance for the free 80 movement of the cable longitudinally through the casing when the jaw is in the normal position, as when there is no load or strain on the cable. To provide for normally retaining the jaw yieldably engaged 85 with the leads of the cable, a looped spring 17, embracing a stud 18 anchored transversely in the opening 5 of the casing, is confined at its free ends between a second stud 19 and the lower edge of said jaw at 90 one side of its pivotal axis for exerting pressure thereon to crowd said jaw in a direction to carry the major portions of the cam faces thereof into binding engagement with said leads. A lifting pin 20 anchored in the 95 body of the jaw and extending laterally and freely through arcuate apertures 21 in the side walls of the casing affords means by which the jaw may be rocked against the tension of the spring 17 to release the cams 100 from bearing engagement with the cable and enable it to be drawn freely through the casing.

With the parts in the position as in Fig. 2, in which the loop of the cable is shown as 105 engaged within an eye or loop 22, representing the load or object with which the cable is to be made fast under tension, it will be apparent that as stress is applied to the body and looped portions of the cable the 110 tendency will be to draw the leads thereof in opposite directions out of the casing, and

as these leads are engaged with the cams of the jaw under the crowding tension of the spring thereon, movement of the leads will effect a corresponding movement of the jaw 5 in a direction to firmly force said leads into gripping engagement with the embracing walls of the casing under the wedging pressure of the cams of said jaw. By this arrangement the gripping action of the jaw, 10 aside from the initial pressure of the spring normally retaining it engaged with the leads of the cable, is automatically controlled by the stress exerted upon the cable, hence, the greater the load the more firmly the cable 15 will be gripped, and when the strain thereon is relieved the lifting pin may be manipulated to rock and release the jaw and enable the cable to be readily adjusted within the casing.

20 We claim:

1. A cable grip comprising a hollow casing having opposed arcuate passages for the reception of the leads of a cable, and a gripping jaw pivoted within said casing and having opposed cam faces reversely engageable respectively with the leads of said cable to wedgingly confine the same against the walls of said passages, said jaw being slideable transversely of said leads to equalize 30 its clamping effect thereon.

2. A cable grip comprising a hollow casing having opposed arcuate passages for the reception of the leads of a cable, a gripping jaw pivoted within said casing and having 35 reversely opposed cam faces rotatably engageable simultaneously with the leads of said cable to wedgingly confine said leads respectively in said arcuate passages, and yieldable means restraining said jaw rotatably to normally retain said cams engaged 40 with the leads of said cable.

3. A cable grip comprising a hollow cas-

ing having openings in opposite ends thereof for the passage of a cable therethrough, a gripping jaw pivotally and slidably supported in said casing and having eccentric engagement with said cable to wedgingly confine the same against withdrawal therefrom, means normally retaining said jaw yieldably engaged with said cable, and means to manually retract said jaw against said retaining means. 45

4. A cable grip comprising a hollow casing having opposed arcuate passages for the reception of the leads of a cable, a gripping jaw pivoted within said casing and having opposed cam faces reversely engageable respectively with the leads of said cable to wedgingly confine the same against the walls of said passages, said jaw having an elongated aperture embracing its pivotal axis to permit lateral movement thereon, and means yieldably restraining said jaw rotatably to normally retain the cam faces thereof engaged with leads of said cable. 50

5. A cable grip comprising a hollow casing having opposed arcuate passages for the reception of the leads of a cable, a gripping jaw pivoted to swing and to move transversely within said casing and having reversely opposed cam faces engageable respectively with the leads of said cable to wedgingly confine the same against the walls of said passages, a spring interposed between said casing and said jaw and acting on the latter to retain the cams thereof yieldably engaged with the leads of said cable, and a projection on the jaw freely extending through said casing and operable to retract said jaw against the tension of said spring. 70

In testimony whereof we sign this specification.

THOMAS J. CRAVEN.
DANIEL J. CRILLY.
